FEEDER FOR FLUID CURRENT CONVEYERS

Haavard Kronstad, near Mahoningtown, Pa.

Application April 12, 1951, Serial No. 220,672

14 Claims. (Cl. 302—49)

1

This invention relates to the feeding to a pipe line of pulverized, granular, and other material capable of being propelled in a fluid-current conveyor.

It is an object of the invention to provide improvements in apparatus for that purpose that includes a drum-like housing containing a feed-wheel formed with radial vanes affording pockets that receive the material at one place of their revolution and from which the material is blown at another place into a pipe line or other conveyor conduit.

More specifically, it is an object of the invention to provide means for easy axial adjustment of the wheel to compensate for wear of certain parts during rotation of the wheel.

Further, it is an object to provide, in apparatus of that kind, a formation and arrangement of parts that makes practicable the easy disconnection and displacement of elements and reassembly of elements when it is necessary to remove worn parts and to substitute unworn ones.

Moreover, it is an object to provide, in such an apparatus, such an arrangement and coordination of parts such as constitutes a compact and satisfactory machine, as hereinafter set forth.

When considered with the description herein, characteristics of the invention are apparent in the accompanying drawing, forming part hereof, wherein an adaptation of the invention is disclosed for purpose of explanation.

Like reference-characters refer to corresponding parts in the views of the drawing, of which—

Fig. 1 is a longitudinal section on line 1—1,

Fig. 2;

Fig. 2 is a transverse section on line 2—2,

Fig. 1;

Fig. 3 is a transverse section on line 3—3,

Fig. 1;

Fig. 4 is a transverse section on line 4—4, 40

Fig. 1.

The apparatus includes a base 5, on which is mounted a support part 6 of a drum-like or circular housing or casing 7.

The housing has a side wall 8 and an opposite side wall 9 of substantially circular plate-like form and disposed substantially parallel to each other. A closing peripheral wall 10 is attached to, or may be made integral with the side wall 8. The wall 10 has an inner smooth surface 11 that is concentric with, and inclined longitudinally of the apparatus to, a drive shaft hereinafter referred to. The wall 10 is formed at its edge remote from the wall 8 with a radially and outwardly disposed flange ring 12, against which the wall 9 closely

2

fits and to which it is removably secured. These walls encompass a feed chamber, into an upper arc of which leads a feed conduit 13 through a feed port 14 and from the opposite lower arc of which a discharge port 15 communicates with a discharge conduit 16 connectable with a conveyor conduit.

The feed conduit is provided with an air-release vent 17, and air-release vents 18 are in upper portions of the housing walls 8, 9, and 10.

Each of the side walls 8 and 9 has a central opening of a size to accommodate certain parts later referred to, the openings being coaxial with the drive shaft.

The wall 8 is formed around its opening with an outwardly extending tubular part 19, which has at its outer end a radially disposed flat ring 20.

A plate 21 conforms to and is fixed closely against the ring 20. The plate is an outer end part of a hollow fixed nave 22, which extends through the tubular part 19 into and across the feed chamber into the opening of side wall 9, and which is held against rotation by the plate 21. A compressed air conduit 23 is connected to the plate 21 and communicates with the interior of the nave, which is closed at its other end. The nave has an exit port 24 in its side in alignment with the discharge port 15. The outer surface 25 is smooth and of a taper of an inclination opposite to, but of the same angle of inclination as that of, the peripheral wall surface 11; that is, these surfaces have convergent disposition to each other.

35 A feed wheel in the housing rotates on the nave. It includes radial vanes 26, with their inner and outer edges conforming in inclination to, and in contact with, respectively, the outer surface 25 of the nave and the inner surface 11 of the peripheral wall. The vanes are maintained in uniform spaced relation by connection to side plates 27 and 28. The vanes and their connected plates afford pockets into which material is fed through port 14 and from which it is discharged through port 15 by air emitted from the nave port 24.

The side plate 28 of the wheel is connected with an impeller 29. The impeller extends outwardly through the opening in housing wall 9, and an end of the nave 22 fits closely into it. The impeller has a coupling flange 30, on its outer end. This flange is connected to a coupling 31, which is held by set screws 32 fast to a drive shaft 33 running in bearings 34 on columns 35 extending upwardly from the base 5. The shaft is rotated

by a wheel 36 fast thereon, the wheel being driven by any suitable means (not shown).

The end of the nave 22 that fits into the impeller 29 is formed with a socket member 37 into which extends an end part of an adjusting shaft 38, the shaft being secured in the socket by a bolt 39. That shaft is disposed in and extends beyond the outer end of the drive shaft 33. The outer end part of the shaft 38 is screw threaded, as shown at 40, and there it carries an adjusting nut 41 and a lock nut 42. A ball bearing device 43 usually is interposed between the end of the rotating drive shaft 33 and the nut 41.

The material to be conveyed moves from the feed conduit 13 into the pockets between the vanes 26 of the feed wheel, which rotates in direction indicated by the arrow in Fig. 2. The wheel pockets successively reach alignment with the nave port 24 and the discharge port 15, and the material in the pockets is blown into the conduit 16 and into the conveyer pipe with which the conduit is connected.

It is desirable that elements of the feed wheel moving in contact with the outer surface of the nave and with the inner surface of the peripheral wall of the housing shall always have as close a running fit as practicable with those surfaces, so that air and fine material particles may be prevented from leakage to the extent possible. Proper contact of wheel elements with those surfaces may be maintained by axial adjustment of the feed wheel against or with respect to the convergent or wedge disposed surfaces of the nave and the peripheral wall. This adjustment is made by turning the nut 41 on the non-rotating shaft 38 against the outer end of the drive shaft 33 connected with the feed wheel, with the result that wheel surfaces are wedged closer against correspondingly inclined surfaces of the nave and the peripheral wall. If it occurs that too close a fit has been attained, the wheel may be eased off by turning the nut in a reverse direction.

The necessary axial adjustment shift of the drive shaft 33 is not sufficient to appreciably displace the drive wheel 36 from alignment with the transmission element by which it is driven.

The feed wheel may be bodily inserted in and withdrawn from the housing after removal of its side wall 9.

I claim:

1. In apparatus to feed material to a fluid current conveyer, a housing encompassing a feed chamber, having feed and discharge ports, and comprising a peripheral wall defining its perimeter, said wall having an inner smooth circular bearing surface, a nave fixed in said housing concentric with said bearing surface having an outer smooth bearing surface, the bearing surfaces of said wall and said nave being inclined in substantially the same angle with respect to the nave axis and in convergent disposition to each other, a feed wheel rotatable on said nave with a tapered bore conforming, respectively, to the inclination of said wall and nave surfaces, said wheel having pockets communicable successively with said feed and discharge ports, means to rotate said wheel, and means to shift said wheel axially.

2. In apparatus to feed material to a fluid current conveyer, a housing encompassing a feed chamber, comprising a peripheral wall defining its perimeter, said wall having an inner smooth circular bearing surface, said housing having feed and discharge ports, a hollow nave fixed in said housing concentric with said bearing surface, having an exit port opposite to said discharge

5
10

opening and a compressed fluid entrance port, and an outer smooth bearing surface, the bearing surfaces of said wall and said nave being inclined in substantially the same angle with respect to the nave axis and in convergent relation to each other, a feed wheel having a periphery and a tapered bore conforming, respectively, to the inclination of said wall and nave surfaces, said nave being disposed in the bore of said wheel, said wheel having pockets communicable successively with said feed and discharge ports, means to rotate said wheel, and means to shift said wheel axially.

3. In apparatus to feed material to a fluid current conveyer, a housing encompassing a feed chamber, having feed and discharge ports, and comprising a peripheral wall defining its perimeter, said wall having an inner smooth circular bearing surface, a nave fixed in said housing concentric with said bearing surface having an outer smooth bearing surface, the bearing surfaces of said wall and nave being inclined in substantially the same angle with respect to the nave axis and in convergent relation to each other, a feed wheel in said housing comprising radial vanes affording pockets therebetween successively communicable with said feed and discharge ports and having outer and inner edges conforming in inclination, respectively, to and normally in contact with the inclined surfaces of said housing wall and nave, means to rotate said wheel, and means to shift said wheel axially.

4. In apparatus to feed material to a fluid current conveyer, a housing encompassing a feed chamber, having feed and discharge ports, and comprising a peripheral wall defining its perimeter, said wall having an inner smooth circular bearing surface, a hollow nave fixed in said housing concentric with said bearing surface, having an exit port opposite to said housing discharge port, an entrance port for fluid under pressure, and an outer smooth bearing surface, the bearing surfaces of said wall and said nave being inclined in substantially the same angle with respect to the nave axis and in convergent relation to each other, a feed wheel in said housing having radial vanes affording pockets communicable successively with said housing feed and discharge ports and with said nave exit port, and having outer and inner edges conforming in inclination, respectively, to and normally in contact with the inclined surfaces of said housing wall and nave, means to rotate said wheel, and means to shift said wheel axially.

5. In apparatus to feed material to a fluid current conveyer, a housing encompassing a feed chamber, having feed and discharge ports, and comprising a peripheral wall defining its perimeter, said wall having an inner smooth circular bearing surface, a nave fixed in said housing concentric with said bearing surface having an outer smooth bearing surface, the bearing surfaces of said wall and nave being inclined in substantially the same angle with respect to the nave axis and in convergent relation to each other, a feed wheel having a periphery and a tapered bore conforming, respectively, to the inclination of said wall and nave surfaces, said wheel having pockets communicable successively with said feed and discharge ports, a drive shaft connected to said wheel, and means to shift said shaft axially.

6. In apparatus to feed material to a fluid current conveyer, a housing encompassing a feed chamber, having feed and discharge ports, and comprising a peripheral wall defining its perim-

eter, said wall having an inner smooth circular bearing surface, a nave fixed in said housing concentric with said bearing surface having an outer smooth bearing surface, the bearing surfaces of said wall and nave being inclined in substantially the same angle with respect to the nave axis and in convergent relation to each other, a feed wheel having a periphery and a tapered bore conforming, respectively, to the inclination of said wall and nave surfaces, said wheel having pockets communicable successively with said feed and discharge ports, a drive shaft connected to said wheel, an adjusting shaft in said drive shaft fixed to said nave, and means on said adjusting shaft to shift said drive shaft axially.

7. In apparatus to feed material to a fluid current conveyer, a housing encompassing a feed chamber, having feed and discharge ports, and comprising a peripheral wall defining its perimeter, said wall having an inner smooth circular bearing surface, a nave fixed in said housing concentric with said bearing surface having an outer smooth bearing surface, the bearing surfaces of said wall and nave being inclined in substantially the same angle with respect to the nave axis and in convergent relation to each other, a feed wheel having a periphery and a tapered bore conforming, respectively, to the inclination of said wall and nave surfaces, said wheel having pockets communicable successively with said feed and discharge ports, a drive shaft connected to said wheel, an adjusting shaft connected to said nave and extending through and beyond said drive shaft, the outer portion of said adjusting shaft being screw threaded, and a nut on said threaded portion operable against said drive shaft to shift it axially.

8. In apparatus to feed material to a fluid current conveyer, a housing encompassing a feed chamber and comprising a peripheral wall defining its perimeter, said wall having an inner smooth circular bearing surface, a nave fixed in said housing concentric with and having a smooth bearing surface aligned with that of said peripheral wall, one of said bearing surfaces having convergent relation to the nave axis, a feed wheel having a bore in which said nave closely is disposed and having a periphery in contact with and conforming to the bearing surface of said wall, and means to shift said wheel axially.

9. In apparatus to feed material to a fluid current conveyer, a housing encompassing a feed chamber and comprising a peripheral wall defining its perimeter, said wall having an inner smooth circular bearing surface, a nave fixed in said housing concentric with and having a smooth bearing surface aligned with that of said peripheral wall, one of said bearing surfaces having convergent relation to the nave axis, a feed wheel having a bore in which said nave closely is disposed and having a periphery in contact with and conforming to the bearing surface of said wall, a drive shaft connected to said wheel, and means to shift said drive shaft axially.

10. In apparatus to feed material to a fluid current conveyer, a housing comprising a feed chamber and comprising a peripheral wall defining its perimeter, said wall having an inner smooth circular bearing surface, a nave fixed in said housing concentric with and having a smooth bearing surface aligned with that of said peripheral wall, one of said bearing surfaces having convergent relation to the nave axis, a feed wheel having a bore in which said nave closely is

disposed and having a periphery in contact with and conforming to the bearing surface of said wall, a drive shaft connected to said wheel, an adjusting shaft in said drive shaft connected to said nave, and means on said adjusting shaft to shift said drive shaft axially.

11. In apparatus to feed material to a fluid current conveyer, a housing encompassing a feed chamber, having feed and discharge ports, and comprising a peripheral wall defining its perimeter, said wall having an inner smooth circular bearing surface, a nave fixed in said housing concentric with said bearing surface having an outer smooth bearing surface, the bearing surfaces of said wall and said nave being inclined in substantially the same angle with respect to the nave axis and in convergent disposition to each other, a feed wheel rotatable on said nave, a feed wheel having a periphery and a tapered bore conforming, respectively, to the inclination of said wall and nave surfaces, said wheel having pockets communicable successively with said feed and discharge ports, an outwardly extending drive shaft connected to said wheel, and an adjusting shaft connected to said nave and extending outwardly therefrom in said drive shaft, and means on said adjusting shaft to shift said drive shaft axially.

12. In apparatus to feed material to a fluid current conveyer, a housing encompassing a feed chamber, having feed and discharge ports, and comprising a peripheral wall defining its perimeter, said wall having an inner smooth bearing surface, and substantially parallel side walls connected with said peripheral wall and having oppositely disposed openings; a hollow nave fixed in one of said side walls concentric with said bearing surface having an outer smooth bearing surface, the bearing surfaces of said peripheral wall and said nave being inclined in substantially the same angle with respect to the nave axis and in convergent disposition to each other, said nave having a lateral discharge port, and means to supply fluid under pressure to said nave; a feed wheel rotatable on said nave having a periphery and tapered bore conforming, respectively, to the inclination of the bearing surfaces of said peripheral wall and nave, said wheel having pockets communicable with said housing feed and discharge ports and said nave port, said wheel comprising an impeller extending outwardly through one of said housing side walls and having an end of said nave extending into it; a hollow shaft connected to said impeller; an adjusting shaft in said drive shaft fixed to said nave; and means on said adjusting shaft to shift said drive shaft axially.

13. In apparatus to feed material to a fluid current conveyer, a housing encompassing a feed chamber, having feed and discharge ports, and comprising a peripheral wall defining its perimeter, said wall having an inner smooth bearing surface, and substantially parallel side walls connected with said peripheral wall and having oppositely disposed openings; a hollow nave fixed in one of said side walls concentric with said bearing surface having an outer smooth bearing surface, the bearing surfaces of said peripheral wall and said nave being inclined in substantially the same angle with respect to said nave axis and in convergent disposition to each other, said nave having a lateral discharge port, and means to supply fluid under pressure to said nave; a feed wheel rotatable on said nave having a periphery and tapered bore conforming, re-

spectively, to the inclination of the bearing surfaces of said peripheral wall and nave, said wheel having pockets communicable with said housing feed and discharge ports and said nave port, said wheel comprising an impeller extending outwardly through one of said housing side walls and having an end of said nave extending into it; a drive shaft connected to said impeller; and means to shift said drive shaft axially.

14. In apparatus to feed material to a fluid current conveyer, a housing encompassing a feed chamber, having feed and discharge ports, and comprising a peripheral wall defining its perimeter, said wall having an inner smooth bearing surface, and substantially parallel side walls connected to said peripheral wall and having oppositely disposed openings; a hollow nave fixed in one of said side walls concentric with said bearing surface having an outer smooth bearing surface, the bearing surfaces of said peripheral wall and said nave being inclined in substantially the same angle with respect to said nave axis and in convergent disposition to each other, said nave having a lateral discharge port, and means to supply fluid under pressure to said nave; a feed wheel rotatable on said nave having a periphery and tapered bore conforming, respectively, to the
